US00D686669S

(12) **United States Design Patent**
Ashida et al.

(10) **Patent No.:** US D686,669 S
(45) **Date of Patent:** ** Jul. 23, 2013

(54) **CONTROLLER FOR ELECTRONIC COMPUTER**

(71) Applicant: **Nintendo Co., Ltd.**, Kyoto (JP)

(72) Inventors: **Kenichiro Ashida**, Kyoto (JP); **Masato Ibuki**, Kyoto (JP); **Shinji Yamamoto**, Kyoto (JP); **Fumiyo Yoshi Suetake**, Kyoto (JP); **Akiko Suga**, Kyoto (JP); **Naoya Yamamoto**, Kyoto (JP); **Hitoshi Tsuchiya**, Kyoto (JP); **Junji Takamoto**, Kyoto (JP); **Daisuke Kumazaki**, Kyoto (JP); **Yositomo Gotou**, Kyoto (JP); **Takanori Okamura**, Kyoto (JP)

(73) Assignee: **Nintendo Co., Ltd.**, Kyoto (JP)

(**) Term: **14 Years**

(21) Appl. No.: **29/444,645**

(22) Filed: **Feb. 1, 2013**

Related U.S. Application Data

(62) Division of application No. 29/407,699, filed on Dec. 1, 2011, now Pat. No. Des. 681,127.

(57) **CLAIM**

The ornamental design for a controller for electronic computer, as shown and described.

DESCRIPTION

FIG. 1 is a front, left and top perspective view of a controller for electronic computer showing our new design;

FIG. 2 is a rear, right and bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a front, left and top perspective view of a second embodiment of a controller for electronic computer;

FIG. 10 is a rear, right and bottom perspective view of FIG. 9;

FIG. 11 is a top plan view of FIG. 9;

FIG. 12 is a bottom plan view of FIG. 9;

FIG. 13 is a front elevational view of FIG. 9;

FIG. 14 is a rear elevational view of FIG. 9;

FIG. 15 is a left side elevational view of FIG. 9; and,

FIG. 16 is a right side elevational view of FIG. 9.

The broken lines are for illustrative purpose and form no part of the claimed design.
